(57) **CLAIM**

The ornamental design for the portable phone, as shown and described.

DESCRIPTION

FIG. 1 is a perspective view of the portable phone showing our design;

FIG. 2 is a front view thereof;

FIG. 3 is a rear view thereof;
FIG. 4 is a left side view thereof;
FIG. 5 is a right side thereof;
FIG. 6 is a top plan view thereof;
FIG. 7 is a bottom plan view thereof;
FIG. 8 is a front, partially open view thereof with accessory;
FIG. 9 is a perspective, open view thereof;
FIG. 10 is a front, open view thereof;

FIG. 11 is a rear, open view thereof;
FIG. 12 is a left side open view thereof; and,
FIG. 13 is a right side open view thereof.
The broken line showing of an accessory in FIG. 8 is
included for illustrative purposes only and forms no part of
the claimed design.
